ELECTRICAL TRANSMISSION CIRCUIT

Arthur W. Vance, Haddonfield, N. J., assignor to
 Radio Corporation of America, a corporation
 of Delaware

Application May 31, 1935, Serial No. 24,199

8 Claims. (Cl. 178—7.5)

My invention relates to electrical transmission circuits which include transformers and particularly to circuits for supplying a deflecting voltage to electrostatic deflecting plates in cathode ray tubes.

In deflecting a cathode ray electrostatically, it is the usual practice to supply a saw-tooth voltage to the deflecting plates through a power tube and a transformer, the transformer being employed to step up the voltage for obtaining maximum deflection. The transformer is practically open-circuited on the secondary except for the slight capacity of the deflecting plates which is negligible compared to the distributed capacity of the transformer secondary. The effect of this distributed capacity in conjunction with the transformer leakage reactance is to spoil the shape and ratio of the saw-tooth voltage appearing across the secondary. Because of this, there is a definite limit to the number of secondary turns, and, therefore, the secondary inductance, which must not be exceeded if the effect of the distributed capacity is to be kept small enough to be harmless.

Since the transformer is to step up the voltage, it follows that there is also a definite limit to the number of primary turns and, therefore, to the primary inductance whereby the primary inductance is so low that an exciting current of appreciable value must be supplied to the transformer. Of course, if the primary inductance could be made very high, the exciting current would be negligible.

An object of my invention is to provide an improved method of and means for transferring a non-sinusoidal voltage wave through a transformer.

A further object of my invention is to provide an improved electrostatic deflecting circuit of the type employing a step-up transformer.

A further object of my invention is to provide an improved electrostatic deflecting circuit in which the effect of exciting current in the step-up transformer is compensated.

A further object of my invention is to provide an improved method of and means for impressing a substantially perfect saw-tooth voltage wave upon cathode ray tube deflecting plates.

A still further object of my invention is to provide an electrostatic deflecting circuit em-

ploying a transformer in which the step-up ratio of the transformer is such as to give a substantially undistorted voltage wave of maximum amplitude.

Other objects, features and advantages of my invention will appear from the following description taken in connection with the accompanying drawings in which,

Figure 1 is a schematic diagram which is referred to in explaining the invention;

Figures 2, 3, 4 and 5 are curves which are referred to in explaining the invention;

Figure 6 is a circuit diagram of one embodiment of my invention;

Figure 7 is a diagram which is referred to in explaining the operation of the circuit shown in Figure 6; and

Figures 8 and 9 are circuit diagrams of other embodiments of my invention.

Before considering a specific circuit for compensating for the exciting current of a transformer, the problem as a whole will be considered with reference to Fig. 1 in which L_p and L_s represent the inductance values of the primary and secondary, respectively, of a perfect transformer. The power tube is considered a constant resistance generator of impedance R_p and internal voltage E , the voltage E being grid volts times the amplification factor of the tube.

The set-up ratio or turns ratio of the transformer is

$$N = \frac{\text{Secondary turns}}{\text{Primary turns}}$$

Then

$$L_p = \frac{L_s}{N^2}$$

The instantaneous voltages across the primary and secondary are V_p and V_s , respectively.

Since it is desired that a saw-tooth voltage wave be impressed upon the deflecting plates indicated at 1 in Fig. 1, it is assumed that a saw-tooth voltage of peak amplitude V and period T is impressed across the primary. This voltage is represented by the curve in Fig. 2. Its equation is

$$V_p = \frac{2Vt}{T} - V$$

where t is the time measured from the beginning of the period. Also

$$5 \quad V_p = L_p \frac{di_p}{dt}$$

or

$$10 \quad di_p = \frac{1}{L_p} V_p dt = \frac{1}{L_p} \left(\frac{2Vt}{T} - V \right) dt$$

$$I_p = \frac{1}{L_p} \int \left(\frac{2Vt}{T} - V \right) dt$$

$$= \frac{V}{L_p} \int \left(\frac{2t}{T} - 1 \right) dt = \frac{V}{L_p} \left(\frac{t^2}{T} - t + C \right)$$

15 Evaluating C such that the wave shall have no D. C. component:

The D. C. component will be zero if

$$20 \quad \int_0^T i_p dt = 0$$

$$\int_0^T i_p dt = \int_0^T \frac{V}{L_p} \left(\frac{t^2}{T} - t + C \right) dt =$$

$$25 \quad \frac{1}{L_p} \left[\frac{Vt^3}{3T} - \frac{Vt^2}{2} + VCT \right]_0^T = \frac{1}{L_p} \left[\frac{VT^3}{3T} - \frac{VT^2}{2} + VCT \right]$$

Let

$$30 \quad \frac{VT^3}{3T} - \frac{VT^2}{2} + VCT = 0$$

Then

$$C = \frac{T}{6}$$

35 for no D. C. component, and

$$I_p = \frac{V}{L_p} \left(\frac{t^2}{T} - C + \frac{T}{6} \right)$$

which has the wave form shown by the curve in Fig. 3.

40 From an inspection of Fig. 1 it is apparent that

$$E = I_p R_p + V_p$$

Then

$$45 \quad E = \frac{R_p V}{L_p} \left(\frac{t^2}{T} - t + \frac{T}{6} \right) + \frac{2Vt}{T} - V$$

which has the wave form shown by the curve in Fig. 4.

From the last equation it is apparent that 50 the voltage applied to the grid of the output tube must contain two components in order to impress a pure saw-tooth voltage upon the deflecting plates, one component for the output voltage, and another component for the internal 55 drop in the output tube caused by the transformer exciting current.

The transformer ratio N for maximum deflection with given values of L_s and R_p may now be determined as follows:

60 From an inspection of Fig. 4 it is apparent that E is a maximum when $t=T$. Let E_m equal this maximum value. Substituting in the last equation

$$65 \quad E_m = \frac{R_p V}{L_p} \left(\frac{T^2}{T} - T + \frac{T}{6} \right) + \frac{2VT}{T} - V$$

$$= \frac{R_p V}{L_p} \left(\frac{T}{6} \right) + V$$

$$70 \quad = V \left(\frac{R_p T}{L_p 6} + 1 \right)$$

Then

$$75 \quad V = \frac{E_m}{\left(\frac{R_p T}{L_p 6} + 1 \right)} = \frac{6E_m L_p}{R_p T + L_p 6}$$

To determine the value of the secondary voltage V_s :

$$V = \frac{V_s}{N} \quad L_p = \frac{L_s}{N^2}$$

Substituting in the equation for V

$$\frac{V_s}{N} = \frac{6E_m \frac{L_s}{N^2}}{R_p T + \frac{L_s}{N^2} 6}$$

$$V_s = \frac{6E_m L_s N}{TR_p N^2 + 6L_s}$$

Since L_s , R_p , T and E_m are fixed, deflection is greatest when V_s is greatest. To determine the 15 transformer turns ratio N which will give maximum value of V_s ,

Let

$$20 \quad \frac{dV_s}{dn} = \frac{d}{dn} \frac{6EL_s N}{TR_p N^2 + 6L_s} = 0$$

or

$$25 \quad \frac{(TR_p N^2 + 6L_s) 6EL_s - (6EL_s N^2 TR_p N)}{(TR_p N^2 + 6L_s)^2} = 0$$

or

$$\frac{TR_p N^2}{6} = L_s$$

Then

$$30 \quad N = \sqrt{\frac{6L_s}{TR_p}}$$

We may compare the value of the primary inductance L_p with the tube impedance R_p when the above condition for maximum deflection exists as follows:

$$L_s = N^2 L_p$$

Substituting in the equation for N

$$40 \quad N = \sqrt{\frac{6N^2 L_p}{TR_p}} = N \sqrt{\frac{6L_p}{TR_p}}$$

or

$$45 \quad \sqrt{\frac{6L_p}{TR_p}} = 1 \text{ and } R_p = \frac{6L_p}{T}$$

If the fundamental frequency of the saw-tooth = f ,

$$50 \quad T = \frac{1}{f} \text{ and } R_p = 6fL_p$$

This shows that for maximum deflection the impedance of the output tube about equals the reactance of the load at the fundamental frequency of the saw-tooth voltage. If the last equation included 2π instead of 6, they would be 55 exactly equal.

We may now investigate the voltage components of the voltage E as follows:

From the equation for R_p

$$60 \quad L_p = \frac{TR_p}{6}$$

and for maximum voltage $t=T$

Substituting in the equation for E

$$65 \quad E_m = \frac{R_p V}{TR_p} \left(\frac{T^2}{T} - T + \frac{T}{6} \right) + \frac{2VT}{T} - V$$

$E_m = V + V = 2V$ which shows that at the peak value of E the peak value of the saw-tooth component equals the peak value of the integral component.

The preceding calculations have shown that for given circuit constants there is one particular transformer ratio that will produce maxi- 75

mum deflection of the cathode ray. It is now of interest to determine how far the optimum transformer ratio may be departed from without materially changing the maximum value of 5 the deflecting voltage.

In Fig. 5 the maximum deflecting voltage V_s is plotted against a quantity which is a function of N . It will be seen that the curve is rather sharply peaked so that if N is less than about 10 0.5 times the optimum value or greater than about 2 times said value, there is a decided reduction in the value of V_s as compared with its peak value.

Referring now to Fig. 6, an embodiment of my 15 invention is shown applied to the horizontal deflecting circuit of a television receiver. The receiver comprises a cathode ray tube 2 of well known construction having a cathode 3, a control electrode 4, a first anode 6, a second anode 7 20 and a fluorescent screen 8. A pair of deflecting plates 9 are located inside the tube for deflecting the cathode ray in one plane.

As will be described hereinafter, a saw-tooth voltage wave is impressed upon the deflecting 25 plates 9 through a transformer 11 having a primary 12 and a secondary 13. The deflecting plates 9 are connected across the secondary 13 through blocking condensers 14 and 16, and the second anode 7 is connected to the mid- 30 point of a resistor 17 connected across the deflecting plates. By employing this particular circuit the deflecting plates 9 are maintained at the same direct current potential as the second anode 7 and they are varied above and below the second anode potential equal amounts 35 during deflection whereby the electrostatic focusing of the cathode ray is not impaired.

Considering now the circuit for generating the saw-tooth deflecting voltage, impulses are generated 40 by means of a relaxation oscillator 18 such as the blocking oscillator illustrated. The blocking oscillator comprises an electric discharge tube 19 having a cathode 21, a control grid 22 and a plate 23. The plate 23 is supplied with voltage 45 from a suitable source such as a battery 24, this voltage being applied to the plate through a resistor 26 and the primary 27 of a transformer 28. A grid leak resistor 29 is connected between the control grid 22 and the cathode 21. Also a grid 50 condenser 31 in series with a winding 32 of the transformer 28 is connected between the grid 22 and the cathode 21 whereby the plate circuit of the tube 19 is coupled to its grid circuit. The coupling is in such a direction and the grid condenser 31 and grid leak resistor 29 are so adjusted that a charge is built up on the condenser 31 periodically to block the tube, the tube remaining blocked until the charge leaks off sufficiently 55 through the resistor 29. The resulting sharp voltage impulses are transferred through a third transformer winding 33 to the input circuit of an electric discharge tube 34 which may be of the screen grid type having a cathode 36, a control grid 37, a screen grid 38 and a plate 39.

60 The control grid 37 is maintained at a negative bias which is high enough to bias the tube almost to cut-off. This negative bias may be applied in any suitable way as by means of a biasing battery or by means of the self-biasing resistor 41 and a shunting condenser 42 shown in the drawings.

In the plate circuit of the tube 34 there is a condenser 43 across which a saw-tooth voltage is to be produced. This condenser is connected between the plate 39 and the cathode 36, in the

particular circuit shown, the connection to the cathode 36 being through the self-biasing resistor 41. The plate 39 is maintained at a positive potential by means of a connection through a resistor 44 of high resistance value to the positive terminal of the battery 24. The resistance of the plate resistor 44 is high enough to cause the condenser 43 to be charged substantially linearly to produce the gradually changing portion of the saw-tooth voltage wave. Each voltage impulse produced by the oscillator 18 is impressed upon the control grid 37 in the positive direction whereby the tube is made highly conductive and the condenser suddenly discharges therethrough to produce the steep portion of the saw-tooth.

As previously explained, the voltage having a substantially perfect saw-tooth wave form which appears across the condenser 43 cannot be applied directly to the input circuit of the power 20 tube 46 which supplies the transformer 11 because of the exciting current taken by the transformer. Therefore, an electric discharge tube 47 and an associated circuit are provided for the purpose of providing a voltage having both a 25 saw-tooth component and an integral component to the input circuit of the power tube 46. The tube 47 may be of the screen grid type having a cathode 48, a control grid 49, a screen grid 51 and a plate 52. A negative bias having a suitable value for making the tube 47 operate as an ordinary class A amplifier is applied to the grid 49 through a grid resistor 53 by any suitable means such as a self-biasing resistor 54 and a shunting condenser 56. The plate 52 of the tube 30 is connected through a plate resistor 57 to the positive terminal of the battery 24.

In accordance with my invention, a network consisting of a condenser 58 and a variable resistor 59 in series is connected between the plate 40. 52 and the cathode 48, in the particular embodiment shown, the connection to the cathode being through the self-biasing resistor 54.

By referring to Fig. 7, where R_p represents the plate impedance of the tube 47 it will be seen that if a saw-tooth voltage 61 is impressed upon the input circuit of the tube 47 there will be a resulting flow of saw-tooth plate current which will cause a saw-tooth voltage 62 to appear across the resistor 59. The saw-tooth plate current 50 flowing into the condenser 58 will charge the condenser to cause a voltage to appear thereacross which is the integral of the saw-tooth voltage as indicated by the curve 63. Therefore, the sum of the two voltages appearing across the resistor 59 55 and the condenser 58 is a voltage having the wave form shown in Fig. 4, and by properly adjusting the value of the resistor 59 the relative magnitudes of the two components may be made such as to cause a perfect saw-tooth voltage to appear across the secondary 13 of the transformer. It will be understood that the plate impedance R_p is very high compared with the impedance of the network 58-59 so that the plate current is substantially independent of the voltage across the network. The power tube 46 may be of the three electrode type having a cathode 64, a grid 66 and a plate 67. The grid 66 is maintained at a suitable negative bias for causing the power tube to 60 operate as an ordinary class A amplifier. In the circuit illustrated this bias is obtained by means of a self-biasing resistor 68 shunted by a condenser 69, the bias being applied through a grid resistor 71. The network 58-59 is coupled to 75

the input circuit of the power tube 46 through a coupling condenser 72.

A suitable positive voltage is applied to the plate 67 through a choke coil 73, the primary 12 of the transformer 11 having its lower terminal connected to the cathode 64 and its upper terminal connected to the plate 67 through a blocking condenser 74.

It should be understood that my invention is not limited to use in a cathode ray tube deflecting circuit. In a transmission line or cable which must transmit a saw-tooth wave, it is sometimes necessary to match impedances by means of a transformer which introduces distortion because of the exciting current required. In such a circuit an integral voltage component may be supplied to the transformer by means of a network such as described above for the purpose of avoiding the distortion.

Instead of obtaining the integral component by means of the condenser and resistor network shown in Fig. 6, it may be obtained by means of a network such as shown in Fig. 8. In Figs. 6 and 8 like parts are indicated by the same reference numerals. The portion of the circuit shown in Fig. 6 to the right of the dotted line 16 may be replaced by the circuit shown in Fig. 8. The distinction between the two circuits is that a low impedance tube 81, such as a 2A3 type, supplies current to a network in the plate circuit which includes an inductance coil 77 and a resistor 78 connected in series. The impedance of the coil 77 is large compared with that of the resistor 78 whereby a saw-tooth voltage impressed upon the grid of the tube 81 causes a saw-tooth voltage to appear across the inductance coil 77 and an integral voltage component to appear across the resistor 78. The reason for this is evident from the fact that a saw-tooth voltage applied across an inductance coil causes current to flow therethrough having a wave form which is the integral of the saw-tooth. This current flowing through the resistor 78, of course, causes a voltage of similar wave form to appear across the resistor.

The saw-tooth voltage component preferably is taken off a potentiometer 79 shunted across the inductance coil 77.

A voltage wave having saw-tooth and integral components may be obtained by various other circuits. For example, as shown in Fig. 9, the condenser 58 may be replaced by a tuned circuit 82-83 of the character described and claimed in my copending application Serial No. 744,533, filed September 18, 1934, and assigned to the same assignee as this application. Also, the saw-tooth component and the integral component may be produced by two separate tubes and combined later in a common circuit instead of being produced and combined in the same network.

The values of certain elements in the circuits shown in Figs. 6 and 8 are indicated in ohms, megohms, microfarads, and henries. It should be understood that these values are given merely by way of example and may be varied within wide limits. The values indicated are for a circuit designed to produce voltage saw-teeth occurring at the rate of approximately 8000 per second.

It will be apparent from the foregoing description that various other modifications may be made in my invention without departing from the spirit and the scope thereof and I desire, therefore, that only such limitations shall be imposed thereon as are necessitated by the prior art and 75 are set forth in the appended claims.

I claim as my invention:

1. In a cathode ray tube deflecting circuit for impressing a voltage of substantially pure saw-tooth wave form upon a pair of deflecting plates, a pair of deflecting plates, a transformer having a primary and a secondary, the inductance of said primary being so low that an exciting current of appreciable value must be supplied to the transformer, means for coupling said deflecting plates across said secondary, an electric discharge tube having an input circuit and having an output circuit coupled to said primary, and means for impressing a voltage upon said input circuit which has two main components, one of said components having a saw-tooth wave form, and the other component having a wave form which is an integral of said saw-tooth component.

2. In a cathode ray tube deflecting circuit for impressing a saw-tooth voltage upon a pair of deflecting plates, a pair of deflecting plates, a transformer having a primary and a secondary, the inductance of said primary being so low that an exciting current of appreciable value must be supplied to the transformer, said secondary being coupled across said plates, an electric discharge tube having an input circuit and having an output circuit coupled to said primary, and means for impressing a voltage upon said input circuit which has two main components, one of said components having a saw-tooth wave form, and the other of said components having a wave form which is an integral of said saw-tooth component, said means including a network which comprises a reactive element and a resistive element.

3. The invention according to claim 2 characterized in that said network comprises a condenser and a resistor in series.

4. The invention according to claim 2 characterized in that said network comprises an inductance coil and a resistor in series.

5. The invention according to claim 1 characterized in that N is approximately equal to

$$\sqrt{\frac{6L_s}{TR_p}}$$

where N equals the ratio of transformer secondary turns to transformer primary turns, L_s equals the inductance of the transformer secondary, R_p equals the plate impedance of the electric discharge tube, and T equals the period of the saw-tooth voltage.

6. In a cathode ray tube deflecting circuit for impressing a saw-tooth voltage upon a pair of deflecting plates, a pair of deflecting plates, a transformer having a primary and a secondary, said secondary being coupled across said plates and having so few turns that its distributed capacity has a negligible effect upon the action of said deflecting circuit, said primary having fewer turns than said secondary to provide a step-up ratio whereby the impedance of said primary is so low that the transformer draws appreciable exciting current, an electric discharge tube having an input circuit and having an output circuit coupled to said primary, and means for supplying a voltage to said input circuit which has only two main components, one of said components being a saw-tooth component and the other of said components being an integral of said saw-tooth component, the relative magnitudes of said integral component and said saw-tooth component being such as to impress a substantially pure saw-tooth wave across said primary.

7. The invention according to claim 6 characterized in that the peak value of the saw-tooth component is approximately equal to the peak value of the integral component.

8. The invention according to claim 6 characterized in that N is approximately equal to

$$\sqrt{\frac{6L_s}{TR_p}}$$

where N equals the ratio of secondary turns to

primary turns, L_s equals the inductance of the secondary, R_p equals the plate impedance of the electric discharge tube, and T equals the period of the saw-tooth voltage, and further characterized in that the peak value of said saw-tooth component is approximately equal to the peak value of said integral component. 5

ARTHUR W. VANCE.
